(57) **CLAIM**

The ornamental design for a leverage arm for a holster or ammunition holder, as shown and described.

DESCRIPTION

FIG. 1 is a front, plan view of a leverage arm for a holster or ammunition holder.

FIG. 2 is a first side view of a leverage arm for a holster or ammunition holder.

FIG. 3 is a second side view of a leverage arm for a holster or ammunition holder.

FIG. 4 is a bottom view of a leverage arm for a holster or ammunition holder.

FIG. 5 is a top view of a leverage arm for a holster or ammunition holder.

FIG. 6 is a front, perspective view of a leverage arm for a holster or ammunition holder.

FIG. 7 is an alternative front, perspective view of a leverage arm for a holster or ammunition holder.

FIG. 8 is a rotated, front, perspective view of a leverage arm for a holster or ammunition holder.

FIG. 9 is an alternative rotated, front, perspective view of a leverage arm for a holster or ammunition holder; and,

FIG. 10 is a front, plan view of a leverage arm for a holster or ammunition holder attached to an exemplary (unclaimed) holster.

The broken line in the drawings depicts unclaimed subject matter only and forms no part of the claimed design.

1 Claim, 8 Drawing Sheets
